TO THE ROOFING PATENTS COMPANY, OF BUFFALO, NEW YORK, A CORPORATION
OF DELAWARE.

SURFACING-MACHINE FOR ROOFING.

1,384,534.

Specification of Letters Patent. Patented July 12, 1921.

Application filed April 7, 1920. Serial No. 371,981.

To all whom it may concern:

Be it known that we, LOWELL F. LINDLEY and ALEXANDER S. SPEER, citizens of the United States, and residents of Chicago, 5 county of Cook, and State of Illinois, have jointly invented certain new and useful Improvements in Surfacing-Machines for Roofing, of which the following is a specification, and which are illustrated in the accompanying 10 drawings, forming a part thereof.

The invention relates to a machine for producing roofing and has for an object the provision of a machine that will produce roofing having definite areas thereon, surfaced with materials of distinctive appearance. A further object is the provision of roofing which is novel in the manner in which it is cut from the continuous sheet and placed together on a roof.

20 In the drawings—

Figure 1 is a side elevation, diagrammatically shown, of a machine embodying the invention.

Figs. 2, 3, and 4 are edge views of various 25 modifications of disks that may be used, the sheet of roofing being shown in section.

Figs. 5 and 6 are plan views of different forms of continuous sheets provided by the invention.

30 Fig. 7 is a detail plan view showing one form of roofing assembled.

Fig. 8 is a detail section on line 8—8 of Fig. 5, and

Fig. 9 is a plan view of a form of shingle 35 provided by the invention.

The roofing provided by the invention is formed in continuous sheets and afterward cut into strips either lengthwise or crosswise of the original sheet, according to the effect 40 desired, which strips are then assembled on the roof in overlapping relation.

The machine diagrammatically shown in the drawings for producing the roofing, in each of its forms comprises spaced disks 45 mounted on a common shaft, the form and spacing of the disks varying according to the effect desired.

In the form of Figs. 1 and 2 the disks 10, have their edges corrugated and are mounted 50 on a shaft 12. As shown the corrugations are angular but curved corrugations might

equally well be used to secure corresponding change in effect.

For the purpose of producing the design of roofing illustrated in Fig. 5 adjacent 55 disks, in the form shown in Fig. 2, are arranged with their corrugations out of phase, that is to say, oppositely directed crests of corrugations of adjacent disks are circumferentially arranged to be in juxtaposition. 60

The material utilized as a base in the production of the roofing is preferably the well known asphalt saturated "felt." Any desirable or suitable fabric may, however, be used as a base in the carrying out of the invention. 65 The sheet of base material 13 bearing a coat of bituminous material 14 in a sticky condition is led about a guide roller 16, in contact with disks 10, about a second guide roller 11, and between a pair of pressing 70 rollers 17, 18.

The sticky coating may be applied to the sheet 13 by any usual and well known process. The sheet, thus prepared is placed under tension sufficient to cause the edges 75 of the disks to press into the sticky coating and to penetrate substantially to the bottom thereof. The edges of the disks are, as shown, given a blunt form, that they shall not in any manner damage the roofing base. 80

To supply the surfacing material to the machine, hoppers 19, 20, 21, 22 are shown, each provided with a spout 23, 24, 25, 26, to deliver material to a space between the respective disks 10. The material supplied 85 by adjacent spout is preferably of different appearance. That supplied to the space between alternate disks will be alike when a two color effect is desired. The surfacing material used is preferably a granular material produced by a crushing process and is desirably such as has a distinctive color given by nature. A very suitable material is slate which occurs in a variety of pleasing colors and is readily crushed and produces 90 particles of advantageously flattened shape. Other desirable materials are copper slag, shells, gravel and sand.

The sheet base material is shown as being in contact with the disks 10 through considerably more than one half their diameter. 100 The granular material is fed to the spaces

between the disks at such a speed that there will always be a surplus present, which will be carried upward by revolution of the disks until it falls away from the sheet by gravity, 5 only those particles actually adhering to the sheet of base material being carried around roller 11 with the sheet.

It will be evident from the description that the disks of Fig. 1 are so corrugated as 10 to form alternate radial ribs and grooves, and that the adjacent disks are symmetrically arranged so that the ribs and grooves of each disk will register with the ribs and grooves of adjacent disks. The disks are so 15 spaced that there is an appreciable distance between the crests of adjacent ribs of adjacent disks and the roofing sheet forms with these disks a series of pockets in which the granular material such as crushed slate tumbles on the sticky surface of the sheet and coats completely all of the sticky surface with which it comes in contact. Any excess 20 remains in the pocket for future use and is periodically replenished from the hopper above and does not at any time become 25 contaminated with granular material of another color from an adjacent pocket.

After the sheet 13 with its coating 14 and adhering granular material has passed over 30 roller 11 it is led between press rollers 17, 18, which press the granular material firmly into the coating 14 and leave a regular surface.

The surplus granular material supplied to 35 the portion of the base 13 projecting at each side beyond the outer disks 10 will spill off from the edge of the sheet and will be collected and reapplied.

The form of disks illustrated in Figs. 1 40 and 2 will produce a sheet of material such as illustrated in Fig. 5, wherein areas 27 and 28 are preferably of contrasting colors and will be separated by accurately drawn, sharp edged, depressed lines as indicated in Fig. 45 8, which lines will be free of granular material. For use on a roof it is preferred to cut the sheet of Fig. 5 on the dotted lines of that figure and to apply the resulting strip sheets lengthwise upon the roof in overlapping relation as indicated in Fig. 7.

The form and arrangement of disks shown 50 in Fig. 3 will produce the sheet of material shown in Fig. 6, in which the areas 29, and 30 are preferably of contrasting colors separated by depressed lines as above described. This form of roofing is preferably cut into strips transversely of the sheets as indicated by the dotted lines on Fig. 6, which strips 55 may be laid in courses lengthwise of the roof, the strips in each course abutting and the successive courses overlapping. It is preferred to lay the strip of successive courses with the narrow areas in staggered relation to give an effect of "broken joints." 60 The outside edge areas 29 of Fig. 6 are in-

dicated as being one half as wide as the remaining areas of like color. When the strips are abutted these end areas will therefore combine to produce an area of normal width.

The form of machine of Fig. 4 is designed 70 to produce a sheet of material of alternating wide strips of contrasting colors separated by sharp, depressed, unsurfaced lines, as in the other forms described. The thus produced sheet is preferably cut as indicated 75 by the dotted lines on Fig. 4 to produce separate shingles the halves of which are of contrasting colors. Such shingles may be laid with either end exposed to produce an entire roof of either of the two colors which 80 each shingle carries.

The depressed lines have a structural utility in addition to their function of separating the areas of contrasting appearance. Roofing of the nature under consideration 85 is found to have a tendency to buckle or pull into waves, to some extent, no matter how carefully manufactured and laid. In the roof of the present invention such buckling is in part localized by the depressed lines 90 since these lines have less rigidity than the remaining portion of the material.

The disks 10 especially when of the form of Fig. 1 should have the same peripheral speed as the speed of travel of the sheet of 95 material 13 in order that there may be no relative motion between the sheet and the disks. This may be accomplished by propelling the sheet of material and allowing the disks to turn freely and be driven 100 thereby.

While the roofing material is being passed about the disks it will have impressed on it a plurality of wavy lines spaced apart from each other a distance such that the web of 105 material may be split between the lines without the line of cut touching any of the impressed lines. That is to say, the straight lines of cut will be in areas of material which has no impressed marks or lines on it. 110 When the sheets are laid as roofing, each strip will have at its edge a plain margin of uniform thickness and of a single color.

Many modifications may be made in the physical embodiment of the invention without departing from its spirit.

We claim as our invention:—

1. In a surfacing machine, a disk mounted to rotate, and means for passing roofing material provided with an adhesive coating 120 about said disk in contact with an arc of the edge thereof, the disk serving as a marker for impressing a continuous pattern defining line on the material extending longitudinally the full length thereof, and means for feeding granular material at each side of the disk, the disk serving as a partition to separate the material at one side thereof from the material at the other throughout the length of the material, 125 130

- whereby the material will be provided with a pattern consisting of continuous areas extending longitudinally and the full length thereof and separated from each other by 5 the defining line.
2. In a surfacing machine, a disk mounted to rotate, and means for passing roofing material provided with an adhesive coating about said disk in contact with an arc of 10 the edge thereof, the disk serving as a marker for impressing a continuous pattern defining line on the material extending longitudinally the full length thereof, and means for feeding granular material of contrasting 15 colors at the opposite sides of the disk, the disk serving as a partition to separate the material at one side thereof from the material at the other throughout the length of the material, whereby the material will be 20 provided with a pattern consisting of continuous areas extending longitudinally and the full length thereof and separated from each other by the defining line.
3. In a surfacing machine, a disk mounted 25 to rotate, and means for passing roofing material provided with an adhesive coating about said disk in contact with an arc of the edge thereof, the disk serving as a marker for impressing a continuous pattern defining line on the material extending longitudinally the full length thereof, means for 30 feeding granular material of contrasting colors at the opposite sides of the disk, the disk serving as a partition to separate the 35 material at one side thereof from the material at the other throughout the length of the material, whereby the material will be provided with a pattern consisting of continuous areas extending longitudinally and 40 the full length thereof and separated from each other by the defining line, and means to press the adhering granular material into the adhesive coating.
4. In a surfacing machine, a series of disks 45 arranged coaxially and spaced apart from each other, means for passing roofing material provided with an adhesive coating about said disks in contact with an arc of the edge thereof, to form a pocket, the disks 50 serving as markers to impress in the adhesive material pattern defining lines extending longitudinally of the material, means for feeding granular material between the disks, said disks serving as partitions to separate 55 the granular material whereby the completed material will have a pattern consisting of areas extending longitudinally of the material and separated by the defining lines.
5. In a surfacing machine, a series of disks 60 arranged coaxially and spaced apart from each other, means for passing roofing material provided with an adhesive coating about said disks in contact with an arc of the edge thereof, to form a pocket, the disks serving 65 as markers to impress in the adhesive mate-
- rial pattern defining lines extending longitudinally of the material, means for feeding granular material between the disks, said disks serving as partitions to separate the granular material whereby the completed 70 material will have a pattern consisting of areas extending longitudinally of the material and separated by the defining lines, and means to press the adhering granular material into the coating.
6. In a surfacing machine, a plurality of disks arranged coaxially and connected to rotate together, the disks having radially extending corrugations forming alternate ribs and grooves, adjacent disks being symmetrically arranged whereby the ribs and grooves of each disk will register with the ribs and grooves of adjacent disks, said disks being spaced from each other so that there will be an appreciable distance between the 75 nearest portions of adjacent disks for the purpose specified.
7. In a surfacing machine, a plurality of disks arranged coaxially and connected to rotate together, the disks having radially 80 extending corrugations forming alternate ribs and grooves, adjacent disks being symmetrically arranged whereby the ribs and grooves of each disk will register with the ribs and grooves of adjacent disks, means 85 for passing roofing material about the disks to cause said material to be impressed with wavy lines by the peripheral edges thereof, the disks being spaced apart from each other so that the impressed lines on the material 90 will be spaced apart at their nearest points to permit the material to be cut on straight lines with a margin of non-impressed material between the lines of cut and the impressed lines.
8. In a surfacing machine, a plurality of disks arranged coaxially and connected to rotate together, the disks having radially 95 extending corrugations forming alternate ribs and grooves, adjacent disks being symmetrically arranged whereby the ribs and grooves of each disk will register with the ribs and grooves of adjacent disks, means for passing roofing material about the disks to cause 100 said material to be impressed with wavy lines by the peripheral edges thereof, the disks being spaced apart from each other so that the impressed lines on the material will be spaced apart at their nearest points to permit the material to be cut on straight 105 lines with a margin of non-impressed material between the lines of cut and the impressed lines.
9. In a surfacing machine, a plurality of disks arranged coaxially and connected to rotate together, the disks having radially 110 extending corrugations forming alternate ribs and grooves, adjacent disks being symmetrically arranged whereby the ribs and grooves of each disk will register with the ribs and grooves of adjacent disks, means for passing roofing material about the disks to cause 115 said material to be impressed with wavy lines by the peripheral edges thereof, the disks being spaced apart from each other so that the impressed lines on the material will be spaced apart at their nearest points to permit the material to be cut on straight 120 lines with a margin of non-impressed material between the lines of cut and the impressed lines, means for applying granular material to the roofing material on each side of each disk.
- 125
- 130

metrically arranged whereby the ribs and grooves of each disk will register with the ribs and grooves of adjacent disks, means for passing roofing material about the disks to cause said material to be impressed with wavy lines by the peripheral edges thereof, the disks being spaced apart from each other so that the impressed lines on the material will be spaced apart at their nearest points

to permit the material to be cut on straight 10 lines with a margin of non-impressed material between the lines of cut and the impressed lines, and means for applying granular material of contrasting appearance to adjacent spaces between the disks.

LOWELL F. LINDLEY.
